John Francis Verreault, Valdese, N. C., assignor to Dolly Hosiery Mills, Inc., Valdese, N. C., a corporation of North Carolina

Application May 12, 1953, Serial No. 24,979

Term of patent 14 years

(Cl. D47—7)

To all whom it may concern:

Be it known that I, John Francis Verreault, a citizen of the United States of America, residing at Valdese, in the county of Burke, State of North Carolina, have invented a new, original, and ornamental Design for a Sock or Similar Article, of which the following is a specification, reference being had to the accompanying drawing, forming a part thereof.

I claim:

The ornamental design for a sock or similar article, substantially as shown.

JOHN FRANCIS VERREAU LT.
